HAIR WAVING DEVICE

Filed Aug. 13, 1928

WITNESS:

M.S.P. Ford

JOSEPH L. GAIRE,
INVENTOR.

BY *Victor J. Evans,*

ATTORNEY:

UNITED STATES PATENT OFFICE.

JOSEPH L. GAIRE, OF PATERSON, NEW JERSEY.

HAIR-WAVING DEVICE.

Application filed August 13, 1928. Serial No. 299,413.

This invention relates to improvements in hair waving devices.

The primary object of the invention resides in a hair waving device for forming permanent waves in human hair by the use of steam, which is believed more efficient and safer, in that the liability of inflicting burns on the user is practically overcome as the hair to be waved is wound about a curler inclosed in a steam box which is insulated to prevent the steam box from heating up exteriorly.

Another object of the invention is to provide a permanent hair waver which embodies a curler element on which the hank of hair to be waved is clamped and wound, and which is placed with the wound hair thereon, into a steam box constructed of a pair of separable sections held tightly together by suitable clamping means and into which steam is passed to act upon the wound hair to place a permanent curl or wave therein.

With these and other objects in view, the invention resides in certain novel construction and combination and arrangement of parts, the essential features of which are hereinafter fully described, are particularly pointed out in the appended claims, and are illustrated in the accompanying drawing, in which:—

30 Figure 1 is a perspective view of my improved hair waver in use.

Figure 2 is a side elevation of the hair waver.

Figure 3 is an end elevation.

35 Figure 4 is a vertical longitudinal sectional view on the line 4—4 of Figure 3.

Figure 5 is a vertical transverse sectional view on the line 5—5 of Figure 4.

40 Figure 6 is a similar view on the line 6—6 of Figure 4.

Figure 7 is a side elevation of the curler element per se.

Figure 8 is a fragmentary perspective view of the steam box looking at one end thereof.

45 Referring to the drawing by reference characters, the numeral 10 designates my improved hair waving device in its entirety which includes a curler element 11 and a steam box or housing 12 for receiving the same. The

50 curler element comprises an elongated shank 13 which is circular in cross section and gradually decreases in diameter from its opposite ends inwardly to provide a concave surface. Pivoted to a clamping ring 14 encircling one

55 of the reduced ends of the shank, is a clamping tongue 15 of a shape to fit snug against

the shank when in clamping position. The extreme ends of the shank are provided with disks or flanges 16 having aligned sets of openings 17 therein, which sets of openings 60 are at varied spaced distances from the axis of the shank for interchangeably receiving a longitudinal rod 18'. The rod 18' acts to clamp the curler element to the hair of the hank of hair wound about the shank, and may 65 be inserted into any of the sets of openings 17, depending upon the thickness of the wound hair thereon.

The steam box 12 includes a pair of separable housing sections 18 and 19 which are 70 closed at opposite ends and semi-circular in cross section to provide a housing which is annular in cross section when the two sections are in coacting positions. The longitudinal edges of the sections 18 and 19 are turned inwardly to provide retaining flanges 20 for linings of asbestos or other insulating material 21 which serves to prevent the outer surfaces of the steam box from excessively heating up. For removably connecting the sections together, I provide one end of the housing section 18 with an outstanding lug 22 having slots 23 therein for receiving the respective tongues 24 projecting from one end of the section 19. The tongue and slot connection provides a separable hinge joint to allow the section to be swung open and closed, and separated if desired. The sections are securely locked in a closed position by a pivoted bolt 25 mounted on the section 19 which 75 is received in a notched lug 26 projecting from the section 18. A thumb nut 27 is threaded to the free end of the bolt and is screwed down tight against the lug 26 to maintain the edges of the sections in tight 80 engagement with each other.

The section 18 is provided with a nipple 28 centrally thereof to which one end of a steam hose or tube 29 is attached. The other end of the hose connects with a suitable source of steam supply to enable the steam box to be filled with steam during a hair waving operation. Steam vent openings 30 are provided in the housing section 18 to permit a limited amount of steam to escape to prevent any 100 possibility of the steam-box blowing up.

In practice a hank of hair is wound about the curler element 11 by clamping the ends of the hank beneath the tongue 15, whereupon the hank of hair is wound upon the curler element as shown in Figure 4 of the drawings. The curler element with the hair tightly

wound thereon is next placed in a steam box and the same securely clamped in a closed position. The operator proceeds to turn on the steam control valve to permit steam to pass through the hose 29 and fill the interior of the steam box. The action of the heat and steam upon the tightly wound hair produces a permanent wave therein which is believed more efficient than those heretofore produced by other hair waving devices. My hair waver will also be found safe in use as it will not burn the scalp or hair of the user due to the interior insulation and can be applied and removed in more rapid time than other devices of this kind.

It might be well to mention that the shape of the shank and clamping tongue of the curler element permits the perfect winding of uneven cut hair thereon, which adapts the device for use in waving bobbed hair of different style cuts.

While I have described what I deem to be the best embodiment of my invention it is obvious that many of the details may be varied without in anyway departing from the

spirit of my invention, and I therefore do not limit myself to the exact details of construction herein set forth, nor to anything less than the whole of my invention limited only by the appended claims.

30

What is claimed as new is:

1. A hair waving device including a housing embodying a pair of elongated co-acting sections hingedly connected at one end thereof, a hair curler element on which the hair to be waved is wound and being snugly receivable within said housing, means at the other end of said section for locking the same in closed position, and a steam hose connected to said housing for supplying steam thereto. 40

35

2. In a hair waving device, a shank provided with flanges on its outer ends a clamping tongue pivotally mounted on said shank for clamping the ends of a hank of hair before winding thereon, and a rod removably supported by said flanges for preventing accidental unwinding of the hank of hair after winding. 45

45

In testimony whereof I affix my signature.
JOSEPH L. GAIKE.
